X-RAY TUBE

Malvern J. Gross and Zed J. Atlee, Chicago, Ill.,
assignors to General Electric X-Ray Corpora-
tion, a corporation of New York

Application May 11, 1936, Serial No. 78,995

4 Claims. (Cl. 250—35)

The present invention relates to X-ray tubes, and more particularly to an improved cathode structure suitable for use in an X-ray tube of the type in which the anode is rotatable to provide relative motion between the electron beam and the target surface.

It is a primary object of the invention to provide a cathode capable of producing two or more independently usable electron beams of substantially different cross-sectional area which may be projected as substantially parallel elongated focal spots on closely adjacent peripheral elements of a rotating target.

The novel features which we consider to be characteristic of our invention will be pointed out with particularity in the appended claims. The invention itself, however, together with further objects and advantages thereof, will best be understood by reference to the following specification taken in connection with the drawing, in which, Fig. 1 shows in elevation an X-ray tube suitably embodying the invention; Fig. 2 is an enlarged view showing the cathode in section and illustrating the relationship between the cathode and the anti-cathode or target; Fig. 3 comprises a series of schematic views illustrating a particular aspect of the invention, and Fig. 4 comprises a similar group of views illustrating a preferred modification thereof.

One application of the invention is illustrated in Fig. 1, in which we have shown a rotatable anode X-ray tube suitable for use in apparatus of the type disclosed and claimed in our copending application, Serial No. 78,994, filed May 11, 1936, and assigned to the same assignee as the present invention. The tube comprises an evacuated envelope 1 enclosing an anode or target 3, and a cathode 4. The cathode is axially spaced and is offset with respect to the center of the anode and is supplied with heating current and with potential from an external high voltage source (not shown) by means of the lead-in wires 11, 12, 13 and 14.

The anode is mechanically connected to a rotatable structure 6 comprising an electromagnetic rotor 7, for example, of the so-called "squirrel cage" induction type. This preferably consists of a laminated magnetic core having longitudinal slots therein filled with a highly conductive metal as, for example, vacuum-cast copper. The rotatable structure as a whole may be supported on an inwardly projecting portion of a shaft 9 by means of suitable antifriction bearings (not shown). Outside the envelope and in the region 55 of the rotor 7 is arranged an electromagnetic

stator 10 provided with energizing windings 15 for supplying a rotating field effective to induce a turning force in the rotor 7. The details of construction of the anode driving means are disclosed and claimed in our copending application, Serial No. 78,996, filed May 11, 1936, and assigned to the same assignee as the present invention.

The nature of the cathode and anode and of the co-operative relationship between them is well illustrated in Fig. 2. It will be noted that the rotatable anode 3 is provided with a beveled target face 18, suitably consisting of a refractory metal such as tungsten, inclined at an angle shown as about 75 degrees with respect to the axis of rotation of the anode. The cathode, which 15 may be supported by means of a glass-to-metal seal 20 from a reentrant envelope stem 21, comprises a laterally projecting sleeve 23 and an electrostatic focusing cup 25 supported at the extremity of the sleeve. A skirt-like shield 21, mounted 20 at the base of the cathode, serves to intercept random X-ray emanations and electrically charged particles coming from the direction of the anode. The focusing cup is provided in its transverse face with a pair of recesses or depressions, of which only one, designated as 26, is apparent in Fig. 2. These recesses are spaced from one another transversely, that is, in a direction transverse to their major axes. At the bottom of each such recess is arranged a substantially linearly disposed incandescent filament, suitably of tungsten, one of such filaments being shown at 28 in connection with the recess 26. As previously indicated, these are supplied with heating current by means of the in-lead conductors 11, 12, 35 13 and 14 sealed into the glass press 29. In order to permit the cathode structure to be placed as far as possible from the wall of the envelope and thereby to decrease the danger of electrical breakdown, the axis of each filament and of its 40 associated focusing recess is somewhat inclined with respect to the plane of rotation of the anode so as to face toward the outer periphery of the target face.

When a high potential is impressed between the 45 anode and cathode, the electron beam emanating from the heated filament 28 is directed primarily by the electrostatic effect of the walls of the recess 26 so as to form an elongated "focal spot" on the beveled face 18 of the anode 3, the extremities of this spot being represented by the dotted projection lines a, b. Due to the extreme angle of inclination of the target face the corresponding X-ray pattern formed on an external object 30 will represent a fore-shortened projec- 55

tion of the focal spot as indicated at *x*. This mode of concentrating the X-rays emanating from an elongated focal spot obtains the effect of a small X-ray source of high energy content 5 and is very desirable from the standpoint of producing a sharply defined radio-graphic image.

In the practical application of X-ray tubes, and more especially of rotatable anode tubes, it 10 is of great importance that each tube have a wide range of operation in order to avoid the need for frequent substitution of units. While it is possible to vary the intensity of radiation of the X-rays and thereby the depth of their penetration by changing the heating current of 15 a particular filament, the flexibility of an X-ray tube of given size may be still further increased by providing it with a plurality of independently usable filaments having different dimensions or which produce electron beams of different cross sectional dimensions. In Fig. 3 we 20 have shown one example of a cathode construction which takes advantage of this latter possibility.

Here, the lowest view shows the frontal appearance 25 of the cathode structure while the two center views show the cooperative relationship between the cathode and the target face 18 as seen from below. In the center views the cathode is shown as a section taken along the line A—A 30 of the frontal view previously mentioned. As hereinbefore explained, the cathode structure comprises a focusing cup 25 having a pair of elongated recesses 26 and 32 formed in the mutually inclined faces thereof. These recesses 35 may be described as being "approximately radially directed" with respect to the axis of rotation of the anode 3. However, when this mode of description is used herein and in the appended claims, it is to be understood as comprising an 40 arrangement such as that shown in Fig. 3 in which either or both of the recesses may depart somewhat from a precisely radial orientation.

Within the recesses there are provided substantially linear incandescent filaments 28 and 45 33 which are also approximately radially directed with respect to the axis of rotation of the anode. The position of each filament with respect to its corresponding recess is such that electrons emitted from it during the operation 50 of the tube will be projected toward the target face 18 in the form of an elongated beam. Due to the fact that the two faces of the cathode cup 25 are mutually inwardly inclined to face a common region of the target 18, the two beams corresponding 55 to the separate filaments will strike the target at adjacent focal spots which are substantially closer together than the filaments themselves. This is desirable in order to have the central beams of X-rays from each of the two focal spots in approximately the same relation 60 with respect to an external objective.

It will be noted, however, that with the parallel arrangement of filaments shown in Fig. 3, the individual focal spots will not be precisely 65 parallel but will have central axes which if projected will intersect as shown in the two upper views of the figure, which views will be recognized as different aspects of the same target face. This intersection, which may be readily 70 verified as a matter of projective geometry is due to the fact that the cathode filaments and the target surface are relatively inclined with respect to one another.

This means that if the axis of one focal spot 75 is perfectly aligned with respect to an external

radiographic objective, so as to produce the maximum concentration of X-ray energy, as previously explained, the other focal spot will necessarily be somewhat out of alignment and will constitute a more diffused source of X-rays than is desirable. Consequently, in changing from one filament to another in the operation of the tube, the best possible radiographic results will not be attainable under all conditions of use.

This difficulty may be overcome and parallelism of the focal spots assured by arranging the individual filaments as shown in Fig. 4, in which the various views correspond to those already described in connection with Fig. 3. By inspection of these views, it will be seen that if the focusing recess 26' (corresponding to the similarly numbered recess of Fig. 2) is arranged so that the axis of the focal spot produced by an electron beam emanating from the filament 28' assumes the position indicated by the line *a*, *b*, 10 then the complementary filament 33' can be made to produce an electron beam whose focal spot has a parallel axis by disposing the filament itself in a non-parallel position as shown. Functionally expressed, the central planes of the two 15 electron beams should intersect the target face in lines which are essentially parallel and which are substantially closer together than are the filaments themselves. Referred to the cathode structure this means that projections of the filaments 28' and 33' on a plane which is precisely 20 normal to the path of the electron beams should be non-parallel and slightly convergent toward the axis of rotation of the anode or toward the portion of the cathode most nearly approached 25 by the anode surface. The amount of this latter convergence will depend on the relative dimensions and spacing of the electrode parts and on the electrostatic effect of the envelope and may be determined experimentally or by calculation 30 for a particular case so that the focal spots are 35 actually parallel as indicated.

While we have shown particular embodiments 40 of our invention, it will be understood by those skilled in the art that modifications in the structure may be made without departing from our invention, and we aim in the appended claims to cover all such modifications as fall within the true spirit and scope of our invention.

What we claim as new and desire to secure by 50 Letters Patent of the United States is:

1. In an X-ray tube, a rotatable anode having a peripherally extending target surface thereon and a cathode structure axially spaced from the anode, said cathode structure including a plurality of transversely spaced linear filaments each 55 relatively inclined with respect to the target surface and adapted during the operation of said tube to project an electron beam toward a common focal region on said surface, said filaments 60 being arranged approximately radially with respect to the axis of rotation of said anode and being slightly convergent in the direction of said axis thereby to cause said electron beams to form parallel elongated focal spots on said focal region 65 of said target surface.

2. In an X-ray tube, a rotatable anode, a cathode structure axially spaced therefrom, a peripherally extending target surface on said anode angularly inclined away from said cathode structure, said cathode structure including a focusing body having a pair of mutually inwardly inclined surfaces thereon facing toward a common focal region on said target surface, each of said surfaces being provided with an elongated recess 70

therein approximately radially directed with respect to the axis of rotation of said anode, and linear filaments respectively arranged in each of said recesses, said filaments being slightly convergent toward the axis of rotation of said anode.

3. In an X-ray tube, a rotatable anode having a peripherally extending target surface thereon, a cathode structure including a pair of transversely spaced linear filaments each arranged approximately radially with respect to the axis of rotation of said anode, means for connecting said filaments to an energy source, and electrostatic means for focusing the electrons emitted by said filaments into elongated beams the central planes 15 of which intersect a common focal region of said target surface in approximately radially extending lines substantially closer together than said filaments, said filaments being usable independently and being adapted to produce electron 20 beams of substantially different cross-sectional area.

4. In an X-ray tube, a rotatable anode having a peripherally extending target surface thereon and a cathode structure axially spaced from the anode, said cathode structure including a focusing body having a pair of spaced elongated recesses therein approximately radially directed with respect to the axis of rotation of the anode, and independently operable linear filaments respectively arranged in each of said recesses, said recesses being located in surfaces of said focusing body which are mutually inwardly inclined to face toward a common focal region on said target surface, whereby electron beams projected from the respective filaments during the operation of said X-ray tube produce on said common focal 15 region of the target surface elongated focal spots which are substantially closer together than said filaments.
